UNITED STATES PATENT OFFICE.

EDWARD A. HALBLEIB, OF ROCHESTER, NEW YORK, ASSIGNOR TO NORTH EAST ELECTRIC COMPANY, OF ROCHESTER, NEW YORK, A CORPORATION OF NEW YORK.

ELECTRIC SWITCH.

1,231,732.

Specification of Letters Patent.

Patented July 3, 1917.

Application filed June 20, 1914. Serial No. 846,337.

To all whom it may concern:

Be it known that I, EDWARD A. HALBLEIB, a citizen of the United States, and resident of Rochester, in the county of Monroe and 5 State of New York, have invented certain new and useful Improvements in Electric Switches, of which the following is a specification.

This invention relates particularly to electric switches for handling comparatively small currents, with which a snap-contact and break are unnecessary.

One object of the invention is to produce a switch, of simple and compact construction, 15 which shall be reliable in operation and not subject to derangement of its parts. Another object of the invention is to produce a switch of the flush type, in which a number of circuits may be opened and closed at 20 will by the simple operation of sliding buttons from one position to another upon the front or cover-plate of the switch. A third object of the invention is to produce a switch particularly adapted for three-wire electric- 25 lighting systems, in which engagement may be made simultaneously, by a single movable contact-member, with three fixed contact-members, and in which a firm contact between all of the members will always be in- 30 sured.

To the foregoing ends I employ, among other features of construction, a manually-operable switch-member which is provided with a recess in which is mounted a spring- 35 pressed movable contact-member, and this manually-operable switch-member is movable laterally so as to cause the movable contact-member to ride over one or more of the fixed contact-members and thus move into or 40 out of position to engage all of the fixed contact-members simultaneously.

Other objects of the invention, and the features of construction by which they are attained, will be set forth hereinafter, in 45 connection with the description of the preferred embodiment of the invention.

In the accompanying drawings:—

Figure 1 is a front-elevation of a switch embodying the present invention; 50 Fig. 2 is a plan-view of the switch, with a part of the casing broken away to show the interior mechanism;

Fig. 3 is a front-elevation of the switch-casing and the fixed contacts, the cover-plate 55 and the parts carried thereby having been removed; and

Fig. 4 is a section on the line 4—4 in Fig. 2.

The invention is illustrated as embodied in a switch of the flush type. The working parts of the switch are inclosed within a casing comprising a body 5 drawn from sheet-metal, and the front of this body is closed by a cover-plate 6 also of sheet-metal, the cover-plate being secured to the body 60 by means of eyelets 7 passing through the ends of the cover-plate and through flanges 8 on the body 5. These eyelets also serve to receive the screws by which the switch is fastened to a wall, dash-board or other support. 65

The cover-plate is provided with a series of short transverse slots 9 for the reception of the movable switch-members. Each of these switch-members comprises an outer 70 manually-operable part or button 10, and an inner part 11 in the form of a socket-member. The parts 10 and 11 are shown as constructed of metal, and are connected by a neck 12, integral with the part 10, which 75 passes through and is riveted within the end of the socket-member 11. The neck is of such size as to move freely within the corresponding slot 9, while the button and the socket-member slide freely upon the inner 80 and outer surfaces of the plate. In all positions of the button the slot is covered and closed by the button, as shown in Fig. 4, so as to prevent the ingress of foreign substances to the switch-casing. 85

The movable contact-member is mounted partly within the socket-member 11, and is illustrated as a ball 13 of any suitable metal. This ball is seated loosely in a shouldered bushing 14 of insulating material, the 90 bushing fitting loosely in the socket-member and being pressed outwardly by a spring 15 inclosed in the socket-member.

Three fixed contact-members, 16, 17 and 18, coöperate with each movable contact-member, these fixed contact-members being fixed in place, upon a body 21 of insulating material, by means of screw-threaded shanks 19 and nuts 22. The shanks and nuts constitute also binding-posts to connect the contact-members with the conductors of the circuits controlled thereby. 100

As shown particularly in Figs. 3 and 4, the adjacent portions of the fixed contact-members are beveled toward each other so as to 105 form a recess 20 in which the movable contact-member 13 may rest when in closed-cir-

cuit position, and in this position it is in firm engagement with all three of the fixed contact-members owing to the fact that the convex surface which it presents to these members, in combination with the constant pressure of the spring 15, causes the ball to move laterally in any direction necessary to insure such contact.

The outer part of the fixed contact-member 16 is also beveled, but in the opposite direction from the inner part. Accordingly, when the movable contact-member is moved toward open-circuit position it first rides up out of the recess 20 upon the highest part of the member 16, and then engages the outwardly-beveled surface thereon, and this engagement causes the movable switch-member to remain in open-circuit position, owing to the pressure of the member 13 against the inclined surface due to the action of the spring 15.

The use of a spherical movable contact-member not only affords, in a convenient and inexpensive manner, a conductor having the necessary convex surface to coöperate with the fixed contact-members, but it also provides for durability, owing to the fact that at each movement of the switch the ball may rotate more or less, thus bringing fresh parts of its surface into action and preventing excessive wear at any one point. The insulating bushing 14 not only provides the necessary insulation between the member 13 and the other parts of the switch, but it also has the advantage that in case the surface of the ball becomes roughened or provided with protuberances, as sometimes may occur through arcing in the switch, this does not prevent the movable contact-member from having the necessary yielding movement within the socket-member, as might occur in case of a direct metallic contact and close fit between the contact-member and the socket-member.

A valuable feature of the switch herein described resides in the fact that no electrical connections are formed between the movable contact-member or bolt 13, and the parts by which it is actuated and supported. Where such electrical connections are made, as in previously proposed switches, they depend either upon the uncertain contact between the movable member and its supporting-devices, or upon transmission through the spring, and there are well known objections to both of these effects. This arrangement also renders it unnecessary to insulate the sliding-members of the switch from each other, or from the plate upon which they are mounted and guided, and permits the construction of all of these parts of metal.

While I have shown a switch having three movable members or buttons it will be un-

derstood that any convenient number may be employed, and that the invention is not, in general, limited to the embodiment thereof hereinbefore described and illustrated in the accompanying drawings.

I claim:

1. An electric switch having, in combination, a plurality of fixed contact-members, a slotted plate located in front of said contact-members, a manually-operable member movable transversely in a slot in said plate and having a socket opening toward said contact-members, a movable contact-member mounted in said socket and having a convex surface adapted to engage the fixed contact-members simultaneously, in one position of the manually-operable member, and to ride over one of the fixed contact-members when the manually-operable member is moved to another position, and a spring in said socket coöperating with the movable contact-member and acting to hold it in engagement with the fixed contact-members.

2. An electric switch having, in combination, a plurality of fixed contact-members located in a group and providing a recess between their adjacent portions; a spherical contact-member of such size that it may seat in said recess and engage the fixed contact-members simultaneously; a manually-operable member movable transversely with respect to the fixed contact-members and having a socket opening toward said members, the spherical contact-member being mounted in said socket; and a spring in the socket co-operating with the spherical contact-member to force it toward the fixed contact-members.

3. An electric switch having, in combination, a plurality of fixed contact-members located in a group and providing a recess between their adjacent portions; a spherical contact-member of such size that it may seat in said recess and engage the fixed contact-members simultaneously; a manually-operable member movable transversely with respect to the fixed contact-members and having a socket opening toward said members, the spherical contact-member being mounted in said socket; a spring in the socket; and a bushing, of non-metallic material, slidingly mounted in the socket and interposed between the spring and the contact-member, the bushing having a seat for the contact-member whereby the latter is centralized in the socket and separated from the walls of the socket.

In testimony whereof, I affix my signature in presence of two witnesses.

EDWARD A. HALBLEIB.
